UNITED STATES PATENT OFFICE

ERNEST A. ANHEUSER AND GEORGE S. REMIKER, OF MILWAUKEE, WISCONSIN

MOLDING FLASK

Application filed April 30, 1931. Serial No. 534,000.

This invention relates to foundry equipment known as "flasks", which contain the sand wherein is embedded the patterns employed in casting commercial metallic products.

The objects of the invention are as follows:—

The providing of a structure which will eliminate those expenditures heretofore attaching to the manufacture of a necessary flask pattern from which object's impression in the sand a cast flask is obtained. Also, the extended machining processes in order to correct inaccuracies unavoidably present in all cast flasks, both after casting the flask, and again after this piece of equipment has been in use at producing castings.

The providing of flasks whose elements will be physically selective and purposely disposed in a way that will permit of arranging each element chosen for assisting other co-related members to resist warping tendencies caused by alternating experiences which expose the flasks to high and low temperatures. Further, to offer designs that may be repaired with replaced elements having similar physical properties in keeping with the original assembly.

The provision whereby the costly methods of "coring", in order to gain certain ribbed surfaces for "keying in" the sand, are dispensed with through the convenience which allows the introduction of materials already patterned to provide desirable surfaces.

Other advantages will be noted throughout the particular description and pointed out in the appended claim, both of which divisions of this application refer to the accompanying drawing, whose several figures are indexed below.

Fig. 1 is a plan view of a flask unit.

Fig. 2 is a section on line 2—2 of Fig. 1.

Fig. 3 is a section on line 3—3 of Fig. 1.

Fig. 4 is a fragmentary perspective view.

Similar characters of reference apply to like parts throughout the several views. The flask assembly chosen is fully illustrative of the invention, as the identical conditions, here contended with, are considerations which af-

fect the various designs of flask-boxes used in the founder's art.

The molten metal employed in casting flask-boxes, followed by the cooling periods, leaves the units so made incomplete, until the abutting surfaces at A must be accurately machined so that the said surfaces will present smooth and true planes. Later on, after the cast flasks have been in service, the hot and cold experiences cause further distortions which require re-machining to correct them. Other defects happen to flask structures of the cast variety, because of their tendencies to warp out of shape, and, since they are cast as unitary bodies, there is no successful precaution that can be introduced during the casting process which would offset or counteract this tendency through the selection of parts having warp-resisting qualities that would co-act with the remaining parts as a check for preserving correct alignment.

With the methods applied in the present invention, the purposeful selection of structural shapes having known stress-resisting qualities makes it possible and economically practical to determine the definite design for opposing strain effects arising through varying temperatures, and such selections can, at will, be joined together in a manner which does not subject the whole to an enveloping heat such as is met with when casting the flask units by the method now in vogue. When a unit is completed by the concerned process, the structure will be complete as initially intended without the additional expense incurred by way of machining changes. The chosen method of flask assembling is definite; there being no guesswork as to what the outcome will be. The slight irregularities are not appreciable set-backs, and whatever re-machining there may be, later on, will be largely due to replacements required through accidents, or the normal wear-and-tear.

Attention is here directed to the scope of what a "re-machining" process amounts to when correcting the abutting planes at the jointure A. The said process affects the entire square area of the flask's plan, which

area is entirely traversed by the cutting tool. In performing this work the said cutter is subjected to the hardship of encountering numerous abrupt beginnings, or cuts, alternating with open spaces, thereby subjecting the cutter to abuses that are costly and time consuming. With respect to these last considerations the present invention noticeably eliminates the out-of-service periods which 10 reduce the time lengths of a flask's usefulness.

The material employed in the present method of construction is, practically, "wrought", or, "rolled" into densely compact forms, thereby not subject to fracture. Where the elements are of plate-like form these elements, when bent or otherwise distorted, are readily forced back to their original locations instead of having to be entirely 20 replaced as is the case where the units are castings. Where an element must be replaced the newer installation will, in the present invention, be a physically similar addition and not a physical departure, which 25 latter, under heat and cold, will expand or contract in unison with its companion parts.

A flask structure is constructed of framing angles L. The said angles offer their base flanges 1 for opposingly abutting similar 30 flanges 2 of like angles L', shown dotted in Fig. 4. The jointure A occurring between the angles L and L' must be a true plane that coincides with the parting surfaces of a complete assembly which, generally, comprises 35 two units; "drag" and "cope". The said angles co-act, through their welded and perfectly abutting relationship, to resist tendencies to depart from their normal aspects. The angles L are further assisted in resisting distortion by virtue of the necessary ribbing which divides off the area inclosed by 40 said angles. The legs 3 of the angles L will retain their normal aspect through the welding thereto of the plates 4 and 5 which are accurately scribed to the said angles and lend 45 their vertical cross-sectional strength for maintaining the true perpendicular relation desired at the walls or legs 3, which latter return a like function for similarly affecting 50 the plates or ribs 4 and 5. The inclosed flask area may be again divided up by ribs or plates 5' when necessary; these latter plates are welded to the ribs 4, so that a grating of 55 rolled steel members is formed whose individual strengths are determined to be as used, they being, practically, a product forged to a point where they are purposely compressed elements, acting as individual members which oppose changes in each other, a function 60 that cannot reside in a similar arrangement cast unitary. When cast, the ribs would be of plate-shape minus the definite physical properties present in product that has been rolled into the said plate-shape.

65 The plates 4, 5 and 5' may be selected from

stock that is knurled or checkered as at 7 which is a valuable innovation for keying sand that, in practice, is tamped between the said plates. To acquire this advantage in a cast flask, there would have to be separate 70 cores for each opening occurring in the rib-divided area.

The construction of a flask by welding the several parts together can be done in such a manner that the high temperatures will not 75 affect areas great enough to overcome the methods of clamping together employed in assembling structures of this kind. Accessories used on flask-boxes, such as trunnions 80 6 or other requisites, can be accurately located and attached without experiencing the frequently occurring hardship, in large cast flask-boxes, of having to cut off the integral trunnion element and relocate same with respect to the center of gravity, which is not 85 always where same was assumed to be in the cast flask's pattern. In the present invention there is no costly pattern required. When the welding is completed the flask-box 90 is ready for foundry service. The elements employed, even when heated in the molding processes, return to their shapes while cooling off. When they are deformed or broken, through long service, the necessary parts are 95 readily installed, if need be, or straightened out by force, which latter is not a convenience with a cast unit.

Many forms of flask-boxes, constructed of wrought steel, in the manner here described, 100 can be forced into correct alignment under forces, as by hammering, that would destroy a cast-metal product which latter material is not tractable under any force tending to bend it back to a shape it has departed from. Further, the inconveniences of "blow-holes", 105 "cracks" and other defects, common to cast structures, are not contingencies to be reckoned with in the structure here considered.

Having described the invention what is 110 claimed as being patentably novel and desired to protect by U. S. Letters Patent, is:

In a flask box the combination, a rectangular inclosure, unitary angle elements of relatively heavy forged product integrally joined 115 together to form the walls of said inclosure, said elements offering outwardly extending webs abuttingly disposed in a plane normal to said walls and coincident to the parting-surface plane of said flask box, and individual embossed plates integrally united as a grating to divide and sub-divide the aforesaid inclosure.

In testimony of which we hereunto affix our signatures.

ERNEST A. ANHEUSER.
GEORGE S. REMIKER.
